PLATEN PRINTING PRESS

Lawrence R. Johnson and Alexander Black, Cleveland, Ohio, assignors to The Chandler & Price Company, Cleveland, Ohio, a corporation of Ohio

Application February 28, 1934, Serial No. 713,290

14 Claims. (Cl. 101—338)

This invention relates, as indicated, to platen printing presses, but has reference more particularly to mechanism for reversing the direction and varying the extent of each rotative movement of the ink disks of such presses.

For the purpose of supplying ink to the form contacting rollers of platen type printing presses, such presses are usually provided with a disk which receives the ink from a fountain or similar device and is intermittently rotated in response to the oscillative movement of the form-carrying bed, the object of such rotation being to insure a uniform distribution of the ink to the rollers. The direction of rotation of the ink disk, as viewed from the front of the press is usually clockwise and the extent of each rotative movement of the disk is generally fixed.

It has been the general observation of those skilled in the use of platen presses that when the direction of rotation of the ink disk is clockwise as stated, a larger proportion of the total ink supply accumulates at the right side of the disk than at the left side, the terms "right" and "left" being employed here with reference to the disk as viewed by an observer standing in front of the press and facing the form carried by the oscillating bed. Consequently, it is the usual practice for the type and/or form setter to build up the right side of the form more heavily than the left side so as to utilize the ink most efficiently.

It is frequently desired or necessary, however, to build up the left side of the form more heavily than the right, as in certain types of color work, or to build up the form more or less uniformly. Moreover, it is desirable at times to vary the extent of each rotative movement of the ink disk, as this has also been found to produce a desired variation in the manner in which the ink is distributed to the form rollers and form.

The present invention accordingly has as its primary object the provision of means for controlling the manner in which the ink is distributed to the ink disk, form-contacting rollers and form of platen type presses.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation of a portion of a platen type printing press having embodied therein mechanism for reversing the direction of rotation of the ink disk as well as means for varying the extent of each rotative movement of the disk; Fig. 2 is a rear elevation of the portion of the press shown in Fig. 1; Fig. 3 is a view similar to Fig. 1, but showing a slightly different form of means for varying the extent of each rotative movement of the disk; Fig. 4 is a rear elevation of the press shown in Fig. 3; Fig. 5 is a view similar to Figs. 1 and 3, but showing a different type of ink-disk reversing mechanism; Fig. 6 is a rear elevation of the press shown in Fig. 5; and Figs. 7 to 11 inclusive are views of another modified form of the invention.

Referring more particularly to the drawings, there is shown in Figs. 1 and 2 a printing press of the Gordon or platen type, comprising a platen 1 and a bed 2, which carries the form 3 and is suitably oscillated with respect to the supporting frame (not shown) of the press, as by means of a crank-rod 4 connected to a back-shaft 5 journalled in the rearwardly extending arms 6 of the bed.

Mounted on the arms 6 of the bed is an inverted U-shaped bracket 7, upon which is rotatably supported the ink-disk 8, which is adapted to receive ink from a fountain or similar device (not shown) and transfer the same to rollers (not shown) carried by oscillatory frame members 9 and 10, the rollers in turn distributing the ink to the form 3. Oscillation of the roller-carrying frame members 9 and 10 is effected by a link or pitman 11.

The ink-disk 8 is provided with a rearwardly extending stud-shaft 12, to which is affixed a bevel-gear 13, whereby the disk may be rotated as by means of a bevel gear 14. Gear 14 is mounted on a sleeve 15 which has mounted on its opposite end a bevel gear 16. The sleeve 15 is mounted on a shaft 17 and may be moved along this shaft so as to bring one or the other of the bevel gears 14 and 16 into mesh with gear 13, a set-screw 18 being provided to lock the sleeve to the shaft 17 after the desired engagement or meshing of gears has been effected. The shaft 17 is journalled in the arms of the bracket 7 and is provided at one end with a clutch 19, which may be in the form of a silent friction clutch, operable by a lever 20 or the like. Intermittent rotation of shaft 17 is effected by means of a cam 21 which is affixed to frame member 10 and engages a roller 22 mounted on a carrier 23, which

is secured to the lever 20, as by means of a set-screw 24. Upon rotation of the frame members 9 and 10 in a clockwise direction, as viewed in Fig. 1, the cam 21 will elevate the roller 22 and 5 thereby rotate the shaft 17.

It will be obvious from the foregoing description that the ink-disk 8 may be rotated in a clockwise or counter-clockwise direction, depending upon whether the gear 14 or gear 16 is 10 brought into engagement with the gear 13, and that either side of the disk may, in this manner, be provided with the larger supply of ink. When the gear 14 is in mesh with gear 13, as shown in Fig. 2, the right side of the disk, as viewed from 15 the front of the press, will accumulate the larger proportion of the ink supply, whereas, when the gear 16 is in mesh with the gear 13, the left side of the disk will accumulate the larger amount of ink. It will also be obvious that if the sleeve 20 20 15 is shifted and locked to the shaft 17 in such a manner that neither of the gears 14 or 16 is in mesh with gear 13, the disk will remain stationary, and the ink will be carried directly to the form. Furthermore, by shifting the position 25 of the roller-carrier 23 along the lever 20, the extent of each rotative movement of the ink-disk, or rather the length of the arc through which the disk will rotate upon each oscillation of the cam 21, may be varied within predetermined limits. 30 If the roller 22 is shifted so as to rest on the forward portion 21a of the cam 21, the lever 20 will not be oscillated, and consequently the disk 8 will remain stationary, even with the gears 14 or 16 35 in mesh with the gear 13.

35 In that form of the invention shown in Figs. 3 and 4 intermittent rotation of the shaft 17 is effected by the cam 21, which engages a roller 25 mounted on one end of an arcuate lever 26, the opposite end of which is pivotally mounted as at 40 27 on one of the arms of bracket 7. The lever 26 is provided with an arcuate slot 28 so as to provide an adjustable connection for one end of a clutch-operating lever 29, a nut 30 being provided to secure the lever 29 in adjusted position. The 45 aforesaid adjustment provides a means of varying the extent of each rotative movement of the disk 8. If the lever 29 is so adjusted as to connect with lever 26 at a point substantially coinciding with the center of the pivotal mounting 27, the lever 50 29, and consequently, the disk 8 will remain stationary. This provides a method of maintaining the ink disk stationary without disturbing the meshing of gears 14 or 16 with gear 13. It will also be noted that roller 25 always bears on the 55 same portion of cam 21, so that the impulse exerted to rotate the disk 8 always has the same characteristics, varying only in degree, as lever 29 is moved in slot 28. This is not true of the device shown in Figs. 1 and 2, in which the roller 60 22 may operate on different portions of the cam.

5 In that form of the invention shown in Figs. 5 and 6, the stub shaft which extends from the ink disk 8 has mounted thereon a friction disk 31, which is slideable towards and away from the disk 8, but is normally urged away from the disk 8 65 and against a roller 32 by means of a coil spring 33, mounted on the stub shaft between the bracket 7 and disk 31. The roller 32 is preferably made of rubber or the like and is splined on, but adjustable to any desired position along the shaft 17. When the roller is in one or the other of the dotted lines positions indicated in Fig. 6, the disk 8 will be rotated in a clockwise or counter-clockwise direction as the case may be, 70 75 but when the roller is in a central position, as

shown in dotted lines, the disk will remain stationary. By adjusting the rollers to various positions intermediate the center and extreme positions, the extent of each rotative movement of the disk 8 may obviously be varied. Rotations of 5 the shaft 17 may be effected by a clutch 34 similar to clutch 19 of Fig. 1, and operable through the intermediary of cam 35, roller 36, and lever 37.

In that form of the invention shown in Figs. 7 to 11 inclusive, a single beveled gear 40 is mounted 10 on the shaft 17 and is always in mesh with gear 13. Shaft 17 has rigidly secured thereon adjacent one end a pair of ratchets 41 and 42, the teeth of one of the ratchets being oppositely directed with respect to those of the other ratchet, so that 15 the disk 8 may be driven in either direction, depending on which ratchet is being driven. The shaft 17 has also pivotally mounted thereon at a point beyond the ratchet a lever 43, which is provided at its free end with a pin or shaft 44 upon 20 which is pivotally mounted a member comprising pawls 45 and 46. Pawl 46 is normally maintained in driving engagement with ratchet 42 as by means of a spring 47 mounted on lever 43 and extending into a recess 48 in the pawl-carrying 25 member. In order to drive the ratchet 42, the lever 43 is oscillated as by means of a second lever 49, which, as shown in Figs. 7 and 9, is actuated by a lever 50. Lever 50 is pivoted, as at 51, to the arm 6 of the bed and is provided at 30 one end with a roller 51. Oscillation of the lever 50 is effected by the cam 52, as in the other forms of the invention.

When it is desired to reverse the direction of 35 rotation of the disk 8, the connection between levers 49 and 43 is loosened, and the levers moved to the respective positions shown in Fig. 8. The lever 49 has an elongated slot 53 in one end to accommodate movement of the parts during the aforesaid adjustment. Pawl 45 is then moved 40 into engagement with the ratchet 41, and is maintained in engagement with the latter by means of the spring 47, which then extends into recess 54 in the pawl-carrying member.

The extent of each rotative movement of the 45 disk 8 may be varied by means consisting of a disk or plate 55 which is mounted on the shaft 17 between the bracket 7 and ratchet 41 and is adjustable circumferentially of the shaft. For 50 this purpose the plate 55 is provided with an extension 56 having an arcuate slot 57, through which a bolt 58 which extends from bracket 7, passes. After the desired adjustment has been 55 made, the plate is clamped to the bracket as by means of a wing nut 59. The plate 55 is provided with an arcuate flange 60, which extends over both ratchets 41 and 42 and covers approximately half the teeth of each ratchet. The flange forms a shroud for the ratchet teeth, upon 60 which shroud the pawls 45 or 46 slide in their return movement during each oscillation of the lever 43. It will be apparent from Fig. 10 that by adjusting the position of the shroud, the number of ratchet teeth exposed to actuation by the pawls may be varied so as to vary the extent of 65 each rotative movement of the disk 8.

It is thus seen that each form of the invention which has been described embodies not only means for changing the direction of rotation of the ink disk, but the extent of each rotative 70 movement as well. It is also seen that the adjustments for accomplishing these ends are effected manually and are therefore at all times within the control of the operator.

Other modes of applying the principle of our 75

invention may be employed instead of the one explained, change being made as regards the mechanism herein disclosed, provided the means stated by any of the following claims or the 5 equivalent of such stated means be employed.

We therefore particularly point out and distinctly claim as our invention:—

1. In a platen printing press, the combination 10 with the ink disk of means for rotating said disk in a clockwise or counterclockwise direction, and means for changing at will the direction of rotation of said disk.

2. In a platen printing press, the combination 15 with the ink disk of means for rotating said disk continually in either direction, and means for changing at will and at any desired point in the rotation of said disk the direction of rotation of the disk.

3. In a platen printing press, the combination 20 with the ink disk of means for varying the extent of each rotative movement of said disk, means for rotating said disk in a clockwise or counter-clockwise direction, and means for changing at will the direction of rotation of said 25 disk.

4. In a platen printing press, the combination with the ink disk of means for varying the extent of each rotative movement of said disk, means for rotating said disk in either direction, 30 and means for changing at will and at any desired point in the rotation of said disk the direction of rotation of the disk.

5. In a platen printing press, the combination 35 with the ink disk of means for varying the extent of each rotative movement of said disk and manually-controlled means for selectively rotating the disk in either direction.

6. In a platen printing press, the combination 40 with the ink disk of manually-controlled means for varying the extent of each rotative movement of said disk and manually-controlled means for changing the direction of rotation of said disk.

7. In a platen printing press, the combination 45 with the ink disk of means for changing the direction of rotation of said disk, said means including a gear rotatable with said disk and a pair of gears, each of which is selectively movable into engagement with said first-named gears.

8. In a platen printing press, the combination 50 with an ink disk requiring a greater accumulation of ink on one side of its ink-receiving surface than on the other side thereof, of means for rotating said disk in a clockwise or counter-clockwise direction according to whether such accumulation is desired on the right or left side respectively of said ink-receiving surface, said directions and sides being considered with reference to the ink-receiving surface of the disk as viewed by an observer facing said surface, said 55

means comprising a gear rotatable about the same axis as said disk and a pair of driving gears for said first-named gear, each of said driving gears being selectively movable into engagement with said first-named gear. 5

9. In a platen printing press, the combination with the ink disk of said press of means for rotating said disk in either direction, said means including a gear rotatable about the same axis as said disk, a shaft rotatable about an axis at an angle to the axis of rotation of said gear, and a sleeve mounted on said shaft, said sleeve provided with a pair of spaced gears, one of which is movable into engagement with said first-named gear to rotate the disk in one direction 10 and the other of which is movable into engagement with the first-named gear to move the disk in the opposite direction.

10. In a platen printing press, the combination 20 with the ink disk of said press of means for rotating said disk in either direction, said means including a friction disk spaced from and rotatable about the same axis as said ink disk, a shaft rotatable about an axis at an angle to the axis of rotation of said friction disk, and a roller mounted 25 on said shaft and movable therealong, said roller being in frictional driving engagement with said friction disk.

11. In a platen printing press, the combination 30 with the ink disk of said press of means for varying the extent of each rotative movement of said disk, said means including a clutch, a clutch operating lever and a cam-operated roller, said roller being adjustably mounted on said lever.

12. In a platen printing press, the combination 35 with the ink disk of said press of means for varying the extent of each rotative movement of said disk, said means including a clutch, a pair of connected levers for operating said clutch, and means for varying the point of connection of said 40 levers.

13. In a platen printing press, the combination 45 with the ink disk of said press of means for varying the extent of each rotative movement of said disk, said means including a friction disk adapted to drive the ink disk and a roller in driving engagement with said friction disk and movable to any desired position along the radius of said friction disk.

14. In a platen printing press, the combination 50 with the ink disk of said press of means for rotating said disk in either direction, said means including a pair of ratchets having oppositely directed teeth, pawls for said ratchets, and a shroud member for varying the number of teeth exposed to actuation by the pawls. 55
